UNITED STATES PATENT OFFICE

153,353

DESIGN FOR A CONTAINER FOR LIQUID COSMETICS

Mauro Herrera, Hollywood, Calif.

Application June 13, 1947, Serial No. 139,665

Term of patent 7 years

(Cl. D58—9)

To all whom it may concern:

Be it known that I, Mauro Herrera, a citizen of the United States, a resident of Hollywood, California, have invented a new, original, and ornamental Design for a Container for Liquid Cosmetics, of which the following is a specification, reference being had to the accompanying drawing, forming part thereof.

Referring to the drawings:

I claim:

The ornamental design for a container for liquid cosmetics, as shown.

MAURO HERRERA.
